ATTORNEY

UNITED STATES PATENT OFFICE.

WESLEY YOUNG, OF SAN FRANCISCO, CALIFORNIA.

PNEUMATIC PRUNING-SAW.

SPECIFICATION forming part of Letters Patent No. 728,069, dated May 12, 1903.

Application filed February 16, 1903. Serial No. 143,579. (No model.)

To all whom it may concern:

Be it known that I, WESLEY YOUNG, a citizen of the United States, residing in the city and county of San Francisco, State of California, have invented an Improvement in Pneumatic Pruning-Saws; and I hereby declare the following to be a full, clear, and exact description of the same.

My invention relates to improvements in apparatus for trimming and pruning fruit-trees and the like, and has reference particularly to a portable sawing device which is operated by compressed air. Its object is to provide a convenient, light, and portable engine and saw which may be easily held in the hands and by which limbs and branches too large for pruning-shears and inconvenient of access for hand-sawing may be severed with ease and in far less time than they could have been by ordinary pruning or hand-sawing methods.

It consists of the parts and the construction and combination of parts hereinafter more fully described, having reference to the accompanying drawings, in which—

Figure 1 is an elevation of the apparatus viewed from one side, the dotted lines showing the relative position of the guides when the saw has nearly severed the limb. Fig. 2 is a view of the opposite side of the saw mechanism and guides. Fig. 3 is a top view of the apparatus.

A represents a tubular handle of suitable light material and of the desired length, having means at its lower end, as at a, for controlling the admission of compressed air or equivalent propelling medium derivable from any convenient source of supply. A cylinder 2 is disposed transversely of and secured to the upper end of the handle, and suitable valve mechanism and connections between the interior of the cylinder and the hollow of the handle are provided which need not here be shown or described in detail, it being understood that on the admission of fluid through the handle the piston-rod 3, to which the saw 4 is attached, will be reciprocated with great rapidity. The piston-rod 3 is slideable in a suitable guide-bracket 5, supported from the cylinder, and the saw is of sufficient

stiffness so as not to be bent or buckled while operating on a limb.

It is to be noted that the saw-teeth are all pitched so that they cut on the inward or draw movement of the saw.

In order to support the apparatus properly upon a limb and to take the strain off of the saw to protect the same, prevent vibration, and obviate any tendency to deviate from the cutting-plane, I provide a yielding guide or feed bar 6. This bar or plate forms a sheathing for the saw on one side and at the end and on top, and normally its lower edge projects below the saw-teeth. Plate 6 is carried on the ends of the rigidly-connected bracket-arms 7, which have a vertical portion slideable in keepers 8 on a stationary part of the apparatus and a horizontal portion attached to a sleeve 9, slideable on handle A. A spring 10, having one end connected with a fixed collar b on the handle and the other to the sleeve, acts upon the latter always to draw it and the bracket-arms and plate 6 downward to cause the latter, as before said, normally to extend below the saw-teeth. The plate has a notch 11, with upwardly-converging walls cut in its side.

In operation the apparatus is hooked over a limb with the latter resting in the notch, so that when the saw is set in motion the plate 8 and the rest of the apparatus is held rigid in relation to the saw. As the saw is advanced through the wood the operator pulls down sufficiently to cause spring 10 to give and let plate 6 rise, so that when the limb is about severed if the limb is a large one the lower edge of the plate may be above the saw.

An apparatus of this sort may be made light and portable and a limb may be cut off in far less time than it could be done by ordinary hand-sawing methods and without the incident fatigue of the latter.

Having thus described my invention, what I claim, and desire to secure by Letters Patent, is—

1. In a tree-trimming apparatus, the combination of a portable support, an engine thereon, a saw reciprocable by said engine, and a yielding guide-plate having a seat to receive the limb.

2. In a tree-trimming apparatus, the combination of a handle, a reciprocating engine thereon, a saw reciprocable by said engine, and a spring-pressed limb-guide in relation 5 to the saw and having a seat for the limb.
3. In a tree-trimming apparatus, the combination of a handle, a reciprocating engine rigid therewith, a saw reciprocable by said engine, and a vertically-yieldable limb-guide 10 in relation to the saw having a seat for the limb.
4. In a tree-trimming apparatus, the combination of a handle, a reciprocating engine thereon, a saw reciprocable thereby, and a 15 vertically-yieldable guide-plate in relation to the saw, said plate having a notch in its under side adapted as a seat for the limb.
5. In a tree-trimming apparatus, the combination of a handle, an engine carried there- 20 by, a saw reciprocable by said engine, and an automatically-yieldable guide-plate in relation to the saw having seating means to receive the limb.
6. In a tree-trimming apparatus, the combination of a tubular handle, a cylinder disposed transversely thereon, a piston reciprocable in said cylinder, connections between said cylinder and a suitable source of power-supply through said handle, a piston-rod and a saw secured thereto, and a vertically-yieldable spring-actuated limb-support in relation 25 to the saw.

In witness whereof I have hereunto set my hand.

WESLEY YOUNG.
